UNITED STATES PATENT OFFICE.

JOHN A. SMITH, OF HARRISBURG, PENNSYLVANIA, ASSIGNOR TO ELLIOTT-FISHER COMPANY,
OF NEW YORK, N. Y., A CORPORATION OF DELAWARE.

CONTROLLING MECHANISM FOR ADDING-MACHINES.

No. 858,634.

Specification of Letters Patent.

Patented July 2, 1907.

Application filed December 29, 1906. Serial No. 350,002.

To all whom it may concern:

Be it known that I, JOHN A. SMITH, a citizen of the United States, residing at Harrisburg, in the county of Dauphin and State of Pennsylvania, have invented a new and useful Controlling Mechanism for Adding-Machines, of which the following is a specification.

This invention relates to calculating machines, and more particularly to what are known as combined type-writing and adding machines. In machines of this 10 character the numeral keys of the typewriter, when depressed to print digits, effect the operation of a computing device through the medium of suitable intermediate connections, which cause the numerical values to be accumulated in the computing device as they are 15 printed on the work sheet. It has been proposed to provide means whereby, when digits are being printed outside of the column to be computed, the keys will be relieved of the burden of the operating connections for the computing device, but will be automatically connected with such operating connections whenever the 20 printing point of the machine is presented opposite the column to be computed, by the movement of the typewriter carriage.

The object of my invention is to carry this proposal 25 into effect by equipping the machine with simple, durable, and efficient mechanism which will automatically connect the keys with the computing device connections whenever the printing point of the typewriter is presented opposite the column to be computed, regardless of the particular location of such column, and which will automatically disconnect the keys from the 30 operating connections whenever the movement of the typewriter carriage presents the printing point of the machine beyond either side of the column.

35 A further object of the invention is to provide means whereby the controlling mechanism above specified may be thrown into or out of operative position so that the computing device may be brought into action at a predetermined point in the carriage movement by the 40 automatic operation of the controlling mechanism, or may remain out of action during the entire carriage movement, as for instance, when it is desired to have the typewriting mechanism wholly independent of the computing device. The latter provision is particularly 45 advantageous for letter writing or other work not requiring addition. It also enables the operator to write or print entirely across the lower portion of the sheet independently of the adding mechanism, after adding a short column of numbers printed on the upper portion 50 of the sheet, or to print the total at the foot of a column or sub-totals below sub-sections of a column without operating the computing device or its connections.

To the accomplishment of these objects and others subordinate thereto, the preferred embodiment of the

invention resides in that construction and arrangement 55 of parts to be hereinafter described; illustrated in the accompanying drawings, and succinctly defined in the appended claims.

In said drawings—Figure 1 is a sectional elevation of an Elliott-Fisher billing machine equipped in accordance with my invention. Fig. 2 is a rear elevation of so much of the same machine as is necessary to show the application of the invention thereto. Fig. 3 is a bottom plan view of the cover-plate of the machine carriage showing certain of the parts assembled thereon. 65 Fig. 4 is a section on the line $x-x$ of Fig. 3. Fig. 5 is a section on the line 5—5 of Fig. 3. Fig. 6 is a detail view of the total key. Fig. 7 is a detail view of the lower indicator plate. Fig. 8 is a perspective view of so much of the controlling mechanism as is exterior to the carriage casing, the parts being shown in full lines in operative position, and the inoperative positions thereof being indicated in dotted lines. Fig. 9 is a view similar to Fig. 8, showing the parts in the positions they assume when the controlling mechanism is operated to 70 effect an operative connection between the computing device and the keys, and Fig. 10 is a detail front elevation of a portion of the computing device, showing the controlling cam attached thereto.

Each part wherever shown is indicated by the same 80 reference character.

In order to understand the controlling mechanism with which this application is directly concerned, it is necessary to have a general understanding of the machine to which it is applied. The Elliott-Fisher billing 85 machine, illustrated in a general way in Figs. 1 and 2, is well known to commerce, and includes a flat platen typewriter equipped with adding mechanism operated from the numeral keys of the typewriter to effect the mechanical addition of a column of numbers as the 90 numbers are printed by the typewriter.

The general organization of the typewriter. The Elliott-Fisher typewriter here shown is exemplified in Patent No. 573,868 to R. J. Fisher and includes a machine frame 1 mounted to travel longitudinally of a flat platen 95 1¹ to space the lines of writing. The frame 1 embraces as elements thereof, a pair of elevated carriage guides 2 which support a carriage 3 upon which is mounted printing mechanism movable transversely of the platen with the carriage to letter space the writing. The upper portion of the carriage is in the form of a casing 4 above which are spaced the numeral and letter keys 5 and 6 having stems 7 connected at their lower ends to key levers 8 fulcrumed within the casing 4. The key levers 8 are in turn connected through draw-wires 9 to the downwardly swinging type bars 10 carried by a type ring 11 suspended from the casing. The carriage 3 is moved to the right by suitable carriage propelling

mechanism, not shown, and its step-by-step advance is controlled by carriage feeding mechanism including an escapement generally indicated at 12 in Fig. 1. This mechanism is of usual construction and causes the carriage to feed forward the distance of one letter space upon the release of a key subsequent to the depression thereof to print a character.

The relation of the computing device to the typewriting machine. (See Patent No. 829,971 to Laganke and Smith.) In rear of the machine frame 1 a guide bar 13 is supported by brackets 14. Supported on the bar 13 is a computing device or register 15 shiftable along the bar to dispose it in proper position relative to a column located at any point of a work sheet supported by the 15 platen. The register is retained in its adjusted position by a locking device 16. The register 15 includes a casing which contains computing and registering mechanism, the specific character of which is immaterial, so far as the present invention is concerned. It may be 20 explained, however, that it includes a series of denominational members 17 in the form of digit carriers or number wheels designed to register hundredths, tenths, units, tens, hundreds, thousands, ten-thousands, hundred-thousands, and millions, the tenths wheel being 25 ordinarily of double width to accommodate the decimal space. Each of these wheels is provided upon its periphery with the digits "0" to "9" inclusive, one digit of each wheel being observable through a sight opening in the casing. Each digit carrier or number wheel 17 is arranged to make nine-tenths of a complete rotation, independently of the other wheels of the series, to present its digits successively before the sight opening, and during its next or tenth increment of movement carries the next wheel to the left a single increment or step for 30 the purpose of transferring the value accumulated upon one wheel to the wheel or member of next higher order. The wheels of the entire series being related to one another in the manner stated, mechanical computations in addition may be effected by moving the wheels corresponding in order or denomination to the order of the digits composing the numbers to be added, a number of increments corresponding to the unitary values of such digits.

The master wheel and its operating connections. The 45 carriage 3 of the typewriting machine supports that portion of the computing mechanism which constitutes the operating means for the computing device or register, which, as already stated, is mounted on the machine frame. The primary element of the actuating 50 mechanism is a master wheel 18 presentable to the number wheels of the register in succession by the step-by-step advance of the carriage in the direction of letter spacing. The master wheel is designed to rotate the number wheels in proportion to the numerical values of the 55 digits embraced by the computation and is operated by the numeral keys of the typewriter, as fully disclosed in the patent to Laganke and Smith, above identified.

The master wheel or actuator is fixedly mounted on 60 a comparatively long actuator shaft 19 and each key is connected to the shaft by one of a series of operating connections each of which includes a ratchet wheel 20 fixed to the shaft and engaged by a driving pawl 21 carried by a driving arm 22 geared to one of a pair of 65 crossed levers 23 and 24. From the front end of the

lever 24 depends a link 25 arranged to swing from the lever and having a separable connection, as indicated at 26, with the stem of a numeral key. The several connections between the shaft 19 and the keys are identical, except that the connections between the 70 crossed levers of the several pairs are disposed in graduated arrangement in order that the movement transmitted from a key to the master wheel will be proportionate to the value of the key. The several interlocking connections 26 between the links 25 and the key 75 stems are of such character that when the links are swung rearwardly, as indicated in dotted lines in Fig. 4, they will be disconnected from the keys so that the latter may be operated to print upon any portion of the work sheet without causing the operation of the computing device. Thus it will be seen that accordingly as the links 25 are in one position or the other, the 80 numeral keys of the typewriter will effect the simultaneous operation of the printing and computing mechanisms or the operation of the printing mechanism 85 alone.

To effect the simultaneous shifting of the links 25 to connect the computing mechanism with the keys, or to disconnect the same therefrom, a swinging yoke 27 is mounted within the casing 4 and comprises a rock 90 shaft 28 having radial arms 29 between the ends of which extend a bar 30 located within vertical slots 31 in the several links 25. Normally, the bar 30 acts as a guide for the links when the latter are reciprocated by the keys 5 to operate the computing mechanism. 95 By swinging the yoke, the bar 30 may be made to move the links into or out of operative connection with the key stems.

Adjacent to one end of the carriage, the shaft 28 is provided with a notched arm 31 engaged by a pin 32 100 projecting laterally from a slide 33 extended through the cover-plate 34 of the carriage casing and having secured to its upper side an upper indicator plate 35 one end of which is turned up to form a total key 36, which may be moved by the operator to shift the slide 105 33 and thus swing the yoke 27 to the position indicated in Fig. 4 for the purpose of disconnecting the keys from the computing mechanism in order that the keys may be operated to print the total at the foot of the column without operating the computing device. 110

In order to indicate whether the keys are connected to the computing device for addition or are disconnected therefrom to permit the printing of the total, a lower indicator plate 37 is secured to the upper side of the cover-plate 34 and is provided with indications, as for 115 instance, the words "total" and "add", either of which is adapted to be exposed opposite a sight opening 38 in the upper indicator plate 35, accordingly as the total key is in one position or the other. Thus, when the parts are in the positions indicated in Fig. 4, the word 120 "total" will appear opposite the slot 38, while the word "add" on the lower plate will be obscured by the upper plate 35. When, on the contrary, the total key is shifted to swing the links 25 into connection with the key stems to organize the device for addition, the word 125 "add" will appear opposite the sight opening, while the word "total" will be obscured. By this arrangement, the operator may tell at a glance whether or not the machine is arranged to print and add or to print alone.

For the purposes of the present invention, the computing mechanism is normally disconnected from the keys, the total key being retained at the rearward limit of its movement, as shown in Fig. 4, by a motor in the form of a spiral spring 39, connected at one end to the slide 33 and at its opposite end to the cover-plate 34. In the patent to Laganne and Smith, before mentioned, the entire mechanism thus far described is disclosed, with the exception that the total key and its manner of connection with the yoke is specifically different and includes no indicator, except the total key itself. The present arrangement is also distinguished from the patented construction by the spring 39 which, instead of acting merely as a detent, actually retracts the slide 33 and operates the yoke 27 to disconnect the keys, unless this action of the spring is resisted in a positive manner.

The means for automatically connecting the keys with the operating connections of the computing device at the proper point in the travel of the carriage, and for automatically disconnecting the keys when the printing point of the machine is beyond the column to be totalized. As has been stated in the prefatory part of this specification, the present invention comprehends the equipment of the machine with an improved mechanism whereby the normally disconnected keys will be automatically connected with the operating connections of the computing device, whenever the movement of the typewriter carriage presents the printing mechanism opposite the column to be computed, and whereby the connection thus established will be automatically broken as soon as the printing mechanism is disposed to print beyond the column or adding field. In the present embodiment of the invention, this mechanism includes a vertically disposed rock shaft 40 journaled in suitable bearings 41 secured to the casing 4 of the typewriter at or adjacent to the rear left hand corner thereof, see Fig. 8. The shaft 40 is provided at its upper and lower ends with horizontal arms 42 and 43, the former extending over the top of the carriage casing and the latter extending rearwardly beyond the same. At its free end the arm 42 is provided with a headed stud 44 resting within a slot 45 in the rear end of a connecting rod 46, the latter being connected at its front end to a stud 47 extending from the plate 35 at a point directly above the slide 33. Normally, that is to say, when the keys are disconnected and the slide 33 is in its rearmost position, as shown in Fig. 8, the front end of the slot 45 is presented to the stud 44. Therefore, if the arm 42 is swung forwardly, as shown in Fig. 9, it will urge the connecting rod 46 longitudinally to advance the slide 33 and thus move the links 25 into connection with the numeral keys against the resistance opposed to such operation by the spring 39. If, on the contrary, the arm 42 is swung rearwardly from the normal position, shown in Fig. 8, the stud 44 will move idly along the slot 45 without effecting any movement of the total key or the parts connected therewith.

Secured to the rearmost wall of the casing 4 is a bracket 48 from which extends a stud 49 supporting a normally vertical lever or trigger 50, extending above and below the stud and arranged to swing to either of the several positions indicated in Figs. 8 and 9. The lever 50 is normally retained in its vertical position by a spring 51 wound around the stud 49 and having its ends disposed vertically at opposite sides of a pin 52 project-

ing from the lower extremity of the lever. It will thus be seen that the spring 51 resists the movement of the lever in either direction and effects the return of the lever whenever the latter is swung. In order to properly retain the spring with both ends in position to contact with the lever, a fixed pin 53 extends from the bracket 48 and is interposed between the end portions of the spring just below the point at which said portions are crossed. The lower end of the lever 50 is connected to the rear end of the arm 43 by a sectional connecting rod 54 between the sections of which is interposed a turn-buckler 55 by means of which the rod is rendered extensible to facilitate the assembling of the mechanism on the machine and to compensate for wear, if necessary.

It will appear, from what has been said, that if the lever 50 is swung from its normal position, indicated in Fig. 8, to the position shown in Fig. 9, the shaft 40 will be rocked in a manner to cause the arm 42 at the upper end thereof to shift the total key for the purpose of connecting the operating connections of the computing device with the numeral keys. It will similarly appear that if the lever 50 is shifted from its normal position to the position indicated in dotted lines in Fig. 8, a reverse operation of the rock shaft 40 will be effected, but the total key will not be operated because the stud 44 will merely move idly in the slot 45 of the connecting rod 46.

The lever 50 is one of the primary elements of the automatic control and is designed to be shifted at the proper time, as indicated in Fig. 9, to render the operation of the computing mechanism possible. This automatic operation of the lever is effected by the movement of the typewriter carriage 3 in the direction of letter spacing, which movement presents the upper end of the lever, preferably provided with inclined or cam faces 56, to a relatively stationary trip or cam 57 which may be and is preferably secured to the casing of the computing device 15 at the lower front corner thereof, see Figs. 1 and 10. This trip or cam 57 is substantially coincident in length with the width of the column to be computed, or adding field. Therefore, as the movement of the typewriter carriage represents the printing point of the machine opposite the highest order of the column, and presents the master wheel 18 in mesh with the denominational member or number wheel of highest order, the lever or trigger 50 will be swung or cammed to the position shown in Fig. 9 by the trip or cam 57, and will be held in such position to maintain the operative connection between the keys 5 and the master wheel 18 as long as said master wheel is opposite the register, or in other words, as long as the master wheel is located in its field of action, which is coincident with the series of denominational members or number wheels 17. As soon, however, as the printing point of the machine moves out of or beyond the column or adding field, and the master wheel moves beyond the number wheel of lowest order, the upper end of the lever 50 will pass beyond the cam 57 and will be instantly restored to its normal position by the spring 51, the total key being simultaneously retracted by the spring 39 to disconnect the keys so that the latter may be operated to print outside of the adding field without being burdened by the computing connections. In other words, the arrangement is such that whenever, in the advance of the typewriter carriage, the numeral

- keys are depressed to print a digit outside of the column or adding field, said keys will operate entirely independently of both the computing device and the operating connections thereof, the keys being automatically connected with the operating connections of the computing device whenever the printing point is located within the adding field and disconnected when the platen and printing mechanism are so related as to permit the printing of digits beyond the column.
- 10 When the carriage is retracted, the lever 50 will engage the trip or cam 57 and will be urged to the position indicated in dotted lines in Fig. 8. This operation will be idle, however, and will not effect any operation of the total key or the parts connected thereto, because 15 the arm 42 will be merely swung rearwardly with the stud 44 playing idly in the slot 45 of the connecting rod 46.
- The means for putting the automatic controlling mechanism out of action.* It will be understood that machines of the character under consideration are used for many different classes of work, as for instance, letter writing, tabulating, listing, and billing. For some classes of work the adding mechanism is a desirable adjunct, but for others the unrestricted independent use 25 of the typewriter is necessary. In still another class of work it is desirable to have the adding mechanism brought into action to totalize a column extending part way down the sheet and to then have the operation of the typewriter entirely independent of the adding mechanism so that matter may be written entirely 30 across the sheet at a point below the column without operating the computing device, even in the event that digits are printed directly below the column or in what would otherwise be the adding field. In order to meet 35 these various requirements, I have combined with the automatic key-connecting or controlling mechanism already described, a simple and convenient device whereby said controlling mechanism may be placed out of action so that the keys will not be connected with the 40 computing device at any time during the carriage travel even though digits are printed in what would otherwise be the adding field. To accomplish this purpose, it is merely necessary to move the lever 50 to a position such, for instance, as that indicated in dotted 45 lines in Fig. 8, in which it will not contact with the cam 57. I therefore mount a bracket 58 at one end of the cover 59, which incloses the operating connections of the computing device, and fulcrum upon said bracket a lever 60 extended upwardly through a slotted flange 61.
- 50 and provided at its upper end with a finger-piece or key 62 by means of which the lever is swung. The lower end of the lever 60 is pivotally connected to the front extremity of a bar 63 provided at its rear extremity with a slot 64 for the reception of the stud 44. Normally the 55 parts are so positioned that the stud 44 is disposed at some distance from the front end of the slot 64 so that the rod 63 will in no way interfere with the movement of the arm 42 when the controlling mechanism is operated to effect the connection of the keys with the computing device connections. When, however, it is desired to place the automatic controlling mechanism out of action, the lever 60 is swung to the position indicated in dotted lines in Fig. 8. This movement of the lever will cause the bar 63 to move rearwardly into engagement with the stud 44 and then urge the stud rear-

wardly for the purpose of swinging the arm 42 to rock the shaft 44 and thus shift the lever 50 to the inoperative position indicated in dotted lines in the figure above mentioned. The lever 60 is retained in this position by a spring detent 65 which engages a notch 66 in the flange 61. When it is desired to again bring the automatic controlling mechanism into position for action, it is simply necessary to move the detent 65 out of the notch and allow a retracting spring 67 to retract the lever 60, thus withdrawing the bar 63 from the stud 44 and allowing the lever 50 to return to normal position under the impulse of the spring 51.

Before concluding, attention may be directed to the fact that the connections between the typewriter keys and the computing device constitute key-operated mechanism controlling the operation of said computing device; that each of the links 25 is a member included in said mechanism and movable into and out of operative position; that the cam 57, the lever 56, and the elements co-operating with these parts to shift the links 85 constitute means operated automatically by the movement of the carriage to control the position of a member of the key-operated mechanism; that the automatically operated means includes a device or abutment 44, and that the lever 60 and the arm 63 constitute 90 means for moving the device 44 and the lever 56 to inoperative positions to render the automatic controlling means ineffective. The automatic controlling means would be rendered equally ineffective, however, by the shifting of either the device 44 or the lever 56 alone 95 to an inoperative position.

It is thought that from the foregoing, the construction and operation of the described mechanism will be fully comprehended, but while the present embodiment of the invention is thought at this time to be preferable, I 100 wish to reserve the right to effect such changes, modifications and variations thereof as may come fairly within the scope of the protection prayed.

What I claim is:—

1. In a combined typewriting and calculating machine, the combination with a typewriter including a carriage, keys, and printing mechanism, of a computing device, key-operated mechanism controlling the operation of the computing device, said mechanism including a member movable into and out of operative position, means operated automatically by the movement of the carriage to control the position of said member, said means including a movable element and a device intermediate of said element and the member, and means for moving said device to an inoperative position independently of the key-operated mechanism to render the automatic controlling means ineffective. 105

2. In a combined typewriting and calculating machine, the combination with a typewriter including a carriage, keys, and printing mechanism, of a computing device, key-operated mechanism controlling the operation of the computing device, said mechanism including a normally inoperative member, means operated by the movement of the carriage to move said member to an operative position, said means including a movable element and a device whereby said element moves the normally inoperative member into operative position, and means for moving said device to an inoperative position independently of the key-operated mechanism and for retaining the device in such position. 110

3. In a combined typewriting and calculating machine, the combination with a typewriter including a frame, a movable carriage, printing mechanism, and keys, of a computing device, a key-operated actuator arranged to operate the computing device, means controlling the operative connection between the actuator and the keys, 130

135

said means including two elements brought into engagement by the movement of the typewriter carriage and one of said elements being mounted to yield when brought into engagement with the other, and means for moving 5 the yieldable element to an inoperative position to prevent the said elements from being brought into contact by the movement of the carriage.

4. In a combined typewriting and calculating machine, the combination with a typewriter including a frame, a 10 movable carriage, printing mechanism movable with the carriage, and keys for operating the printing mechanism, of a computing device mounted on the frame, an actuator mounted on the carriage, and means controlling the operative connection between the actuator and the keys, 15 said means including coöperating elements mounted on the frame and carriage respectively, and brought into engagement by the movement of the carriage, and means for moving one of said elements to an inoperative position and for holding the same in such position to prevent the engagement of the elements.

5. In a combined typewriting and calculating machine, the combination with a typewriter including a carriage, 20 keys, and printing mechanism, of a register, an actuator therefor normally disconnected from the keys, and means including a key for connecting the keys and actuator, an automatically operated device for connecting the keys and actuator, and means including another key for rendering the automatic means inoperative.

6. In a combined typewriting and calculating machine, 25 the combination with a typewriter including a carriage, printing mechanism, and keys, of a register, an actuator therefor normally disconnected from the keys, means for connecting the actuator and keys, said means including a key adapted to be operated manually, and automatic 30 means for operating the key at a predetermined point in the carriage movement.

7. In a combined typewriting and calculating machine, the combination with a typewriter including a carriage, 35 printing mechanism, and keys, of a register, an actuator therefor normally disconnected from the keys, means for connecting the actuator and keys, said means including a key adapted to be operated manually, automatic means for operating the key at a predetermined point in the carriage movement, and means including a second key for 40 rendering the automatic means inoperative.

8. The combination with a register, operating connections therefor, and keys, of means for controlling the operative relation between the keys and said connections, 45 said means including a slide having an opening therein and movable to different positions, and an indicator bearing a plurality of indications one only of which is visible through the opening in the slide in any given position of the latter.

9. The combination with a register, of operating mechanism therefor, and keys, of means including a slide operative to control the coöperative relation between the keys and the actuating mechanism, means operated automatically at a given point in the carriage movement to move the slide, means for operating the slide manually, 50 and reactive means for retracting the slide.

10. In a combined typewriting and calculating machine, the combination with a typewriter including a carriage, 55 keys, and printing mechanism, of a register, an actuator therefor normally disconnected from the keys, means for effecting the automatic control of the connections between the keys and the actuator, said means including a lever movable with the typewriter carriage and a relatively stationary cam disposed to coöperate with the lever at a predetermined point in the carriage movement, and a key 60 for shifting the lever to an inoperative position.

11. In a combined typewriting and calculating machine, the combination with a typewriter including a carriage, 65 keys, and printing mechanism, of a register, an actuator therefor normally disconnected from the keys, and means controlling the connection between the keys and the actuator, said means including a total key, a rock shaft connected to the key, a lever connected to the rock shaft, and a cam disposed to move the lever at a predetermined point in the carriage movement.

80 12. In a combined typewriting and calculating machine,

the combination with a typewriter including a carriage, 85 keys, and printing mechanism, of a register, an actuator therefor normally disconnected from the keys, and means including a slide controlling the operative relation between the actuator and keys, a rock shaft having angularly related arms, a connection between one of the arms and the slide, a lever connected to the other arm, and means for automatically operating the lever at a given point in the carriage movement.

13. In a combined typewriting and calculating machine, 90 the combination with a typewriter including a carriage, keys, and printing mechanism, of a register, an actuator therefor, means including a key operative to control the connection between the actuator and the keys, means for automatically operating the key, said means including a 95 cam and a lever presented in coöperative relation by the movement of the carriage, and a key for moving the lever to an inoperative position.

14. In a combined typewriting and calculating machine, 100 the combination with a typewriter including a carriage, keys, and printing mechanism, of a register, an actuator therefor, an element movable to control the coöperative relation between the keys and the actuator, automatic means brought into action at a predetermined point in the movement of the carriage to move said element, a key lever, and means operated by the key lever to move an element of the automatic mechanism to an inoperative position.

15. In a combined typewriting and calculating machine, 110 the combination with a typewriter including a carriage, keys, and printing mechanism, of a register, an actuator therefor, means controlling the operative connection between the keys and the actuator, said means including a slide, a swinging arm, a connecting rod between the arm and the slide, means for automatically operating the arm 115 at a predetermined point in the carriage movement to operate the slide, a key lever, and means operated by the lever to move the arm to an inoperative position.

16. In a combined typewriting and calculating machine, 120 the combination with a typewriter including a carriage, keys, and printing mechanism, of a register, an actuator therefor, means including a slide movable to control the connection between the keys and the actuator, a total key for manually operating the slide, a rock shaft provided with angularly related arms, a connection between one of said arms and the slide, means including a coöperating cam and lever for operating the other arm of the rock shaft, a key lever, and means operated by the key lever for shifting the rock shaft to render the automatic mechanism inoperative.

17. In a combined typewriting and calculating machine, 125 the combination with a typewriter including a frame, a movable carriage, printing mechanism movable with the carriage, and keys for operating the printing mechanism, of a computing device mounted on the frame, an actuator mounted on the carriage, and means controlling the operative connection between the actuator and the keys, said means including coöperating elements mounted on the frame and carriage respectively and brought into engagement by the movement of the carriage, and a key mounted 130 on the carriage and operative to move one of the elements above specified to an inoperative position.

18. In a combined typewriting and calculating machine, 135 the combination with a typewriter including a carriage, keys, and printing mechanism, of a register, means operated automatically by the movement of the typewriter carriage to operatively connect the keys and register, said means including a slide having an opening therein and movable to different positions, and an indicator bearing a plurality of indications one only of which is visible 140 through the opening in the slide in any given position of the latter.

In testimony, that I claim the foregoing as my own, I have hereto affixed my signature in the presence of two witnesses.

JOHN A. SMITH.

Witnesses:

JORAM ZIEGLER,
P. H. TURLEY.
